UNITED STATES PATENT OFFICE.

CLARENCE LEON GOODRICH, OF HARTFORD, CONNECTICUT, ASSIGNOR TO PRATT & WHITNEY COMPANY, OF HARTFORD, CONNECTICUT, A CORPORATION OF NEW JERSEY.

TOOL-HOLDER.

No. 921,977.

Specification of Letters Patent.

Patented May 18, 1909.

Application filed April 18, 1906. Serial No. 312,426.

To all whom it may concern:

Be it known that I, CLARENCE L. GOODRICH, a citizen of the United States, residing at Hartford, in the county of Hartford and 5 State of Connecticut, have invented certain new and useful Improvements in Tool-Holders, of which the following is a specification.

This invention relates to devices for holding dies and taps, or other screw-cutting tools, and is in the nature of an improvement on the tool-holder covered by U. S. Patent No. 803,981, dated January 2nd, 1906, and to which reference may be had. 10 In said patent, guides for permitting a yielding movement in a spiral path of the device in which the tool is held are set forth, and the present invention comprises improvements in the construction of, and in the manner of 15 mounting said guides, whereby improved results are obtained.

Other improvements relate to means carried by the tool-holder proper for engaging the guides just mentioned, and to means for 20 causing the tool to engage the work under yielding pressure, as will be hereinafter explained.

In the accompanying drawings, Figure 1 is a longitudinal, vertical section of a tool-holder embodying the features of the invention, said section being taken on line 1, 1 of Fig. 2. Fig. 2 is a side elevation. Fig. 3 a front end view; and Fig. 4 a section on line 4—4 of Fig. 2.

Like numerals designate similar parts throughout the several views.

Referring to the drawings, the numeral 1 designates a tubular shank adapted to be received in the socket of a turret or other carrier, and 2 a head rigid with said shank and provided with ears or projections 3 and with sockets 4 at its opposite ends. Clutching guide-arms 5 are pivoted on bolts 6 passing through the ears or projections 3, and each 10 arm projects beyond said ears, and is provided with an inclined side 6' and with a forward end inclined at 7 for a purpose hereinafter described. A socket 8 is formed in each arm 15 back of its pivot, each socket being in alignment with the socket 4 of the head 2, and these sockets are for the reception of coiled springs 9 which normally force the guides 5 to the position illustrated in Fig. 1, and against stop-pins 10, passing through the 20 ears.

Fitted in the bore of shank 1 and passing through the head 2 is the stem 11 of a die or tap-holder 12 provided with a socket 13 in which the tool is secured by a screw 14, or other device (see Fig. 3). This stem is provided with a chamber 15, in which is placed a coiled spring 16, and at the outer end of said spring is a plunger 17 furcated at 18 to straddle a pin 19 passing through the rear end of said stem, and through a collar 20 upon the reduced rear end thereof. An internal thread 21 is formed in the tubular shank 1, and engaging said thread is a plug 22, grooved at 22' to receive a screw-driver. Surrounding the stem 11 and located within the tubular shank 1 is a coiled-spring 23, the inner head of which abuts against the head 2, and its opposite end against the collar 20, as illustrated in Fig. 1.

As shown by Figs. 1 and 4 the stem 11 of head 12 is of cam-shape as at 24. In other words, said stem is concentric for a portion of its periphery, and terminates in a shoulder 25, following which is a curve 26 of less radius. Mounted in a bore of one of the 20 arms 3 of the head 2 is a plug 27, rabbeted at its top to form a shoulder 28 with an inclined surface 29 to permit clearance, the end of the shoulder 28 being in contact with the cam-shaped part of the stem 11. At its end opposite the shoulder plug 27 is rabbeted at 30 to provide a seat for the end of a flat spring 31 held to the arm by screws 32, as illustrated in Fig. 4, and serving to force the plug inward while permitting it to yield in an outward direction when the screw or other object has been threaded and the holder rotates idly with said object. In the head 12, or tool-holder proper, are seated plugs 33, each having an inclined wall 34 at its outer end terminating in a flat surface 35, and each also having an inclined wall 36 located substantially at right angles to the incline 34.

In the operation of the improvement the tool-holder is advanced until the threading-tool engages the work, carried by the usual revolving chuck (not shown) under yielding pressure. On contact of the tool with the work, the head 12 and its stem 11 are forced slightly backward, the stem sliding over the furcated plunger, 17 and compressing the spring 15, thus causing the tool to make proper contact with the work and avoid marking or jamming of the thread thereon at the commencement of the cutting-action. When 110

the screw-cutting tool engages the work the lead of the thread being cut causes the tool-holder to advance along the inclined guides 5 and thus to have a slight rotary movement in 5 a spiral path, thereby precluding binding-action of the plugs 33 and said arms as the head 12 and shank 5 are pulled out by the thread being formed. It will of course be understood that as long as the inclined walls 10 36 of the plugs 33 are in contact with the inclined walls of the arms 5 the tool-holder 12 will remain substantially stationary except as regards the slight rotary and longitudinal movements mentioned, and that when the 15 thread has been completed the plugs 33 will leave the ends of the arms 5 and the head 12 will rotate idly with the screw being formed. When this action occurs, the tool-holder and its shank will rotate in the same direction as 20 the chuck carrying the work, and the cam-shaped portion 24 of the stem will then move by the plug 27, or to the right, as illustrated in Fig. 4, said plug snapping behind the shoulder 28 during such rotation. When the 25 thread of the work has been completed a backward movement will be imparted to the turret slide, in the socket of the turret of which said tool-holder is mounted, and the rotation of the work will also be reversed. When 30 this action takes place the spring 23, which was compressed by collar 20 during the forward movement of the tool-holder toward the work, is free to expand and force the same backward by its action against said 35 collar 20, and the shoulders 25 and 28 of the stem 11 and the plug 27 being in contact will prevent rotation of the tool-holder, and thus permit the rotary work-holder to withdraw the screw from the threading-tool. It frequently happens in the common constructions that when the holder 12 starts to recede, contact will be made with the ends of the arms 5, thereby arresting the rearward movement of said holder and causing damage 40 to the thread. To prevent this action the ends of the arms 5 are beveled or inclined as at 7, and the plugs 33 are also beveled or inclined as at 34, so that when the inclines meet on the return action of said tool-holder, the 45 arms 5 will be raised on their pivots 6, against the stress of the springs 9, thus enabling the plugs to slip by them and avoiding all danger of the arrest of the movement of the retreating tool-holder.

50 In the illustration given the shank 1, its head and the inclined and pivoted guide-arms carried by said head may be termed the "stationary member", while the tool-holder and its stem may be designated as the "movable member". It is obvious, however, that the relation of the parts may be changed in various ways without departure from the invention. So too while the means for holding the tool-holder under yielding pressure when 55 the tool carried thereby engages the work are

preferable, such means may be variously modified without departure from the invention.

It will be apparent from the foregoing description taken in connection with the annexed drawings that my tool holder comprises a tool-carrying member and a head coöperative with each other each of said parts having a projection which projections coöperate to secure a coupling relation between said two parts on the advancing movement of said tool-carrying member. One of these projections is yieldingly mounted radially of the tool holder and is engageable by the other projection on the backward movement 80 of said tool-carrying member during which action said yieldable projection is caused to positively retract by the companion projection so as to avoid injury to the parts as hereinbefore stated. While said projections are 85 shown as duplicated this is not essential nor is it essential on which part of the holder the yieldable projection or projections be mounted although they are shown as carried by the head of the implement and consist of what I 90 have hereinbefore termed guide arms. It is conceivable that in some cases the beveled tips of the yieldable members might be omitted although their presence is very useful. So also these beveled portions might be otherwise disposed within the spirit of my invention the latter contemplating broadly a member which yields or is retracted on the backward movement of the tool-carrying member.

Changes may be made in the form and proportions of the parts, and the inclines on the plugs and arms may be of various angles different from those shown, if desired.

Other stop-devices may also be provided as substitutes for the cam-shaped stem and plug without departure from the invention, which is not limited to the precise details illustrated and described.

Having thus described the invention what I claim is:

1. A tool holder comprising a pair of members one of which has a forward and backward movement with respect to the other, a swinging arm on one of said members and a projection on the other member said projection and swinging arm being coöperative to secure a working relation between said members on the advancing movement of that one which moves forward and backward and said projection serving to swing said arm on the backward movement of said member which moves forward and backward.

2. A tool holder comprising a pair of members one of which has a forward and backward movement with respect to the companion member, swinging arms on the latter member, and devices on the other member for engaging said swinging arms to secure a working relation between the members on the advancing movement and to

swing said arms on the backward movement of said member, which moves forward and backward.

3. A tool holder comprising a tool-carrying member and a head the former having a forward and backward movement with respect to the latter, a spring actuated swinging arm on said head, a device on the tool-carrying member for engaging said arm on the forward movement of said tool-carrying member to secure a working relation between said two first-mentioned parts and said device serving to engage and swing said arm on the backward movement of said tool-carrying member whereby said backward movement can be accomplished without obstruction.

4. A tool holder comprising a tool-carrying member and a head, swinging arms yieldingly carried by said head and having laterally beveled surfaces, and projections on the tool-carrying member the latter being capable of forward and backward movements with respect to said head and said projections bearing against said laterally beveled surfaces on the forward movement of said tool-carrying member to thereby operatively associate said tool-carrying member and head and also permit turning movement of the former and said projections being adapted to engage the tips of said swinging arms on the rearward movement of said tool-carrying member said tips where engaged by said projections being beveled.

5. The combination, with a tool-carrying member having a recessed stem, of a plunger mounted in the recess of the stem; a spring bearing against the rear end of the plunger; a support in which the stem is mounted; means for preventing rotation between the stem and support; and a device on the support, and with which the outer end of the plunger engages.

6. The combination, with a head having a tubular shank, of lever-arms pivoted to said head; springs for normally holding said

lever-arms in position parallel to the head; a tool-holder having a stem mounted in the bore of the head and shank; and inclined stops carried by said tool-holder, and in engagement with the lever-arms.

7. The combination, with a head provided with pairs of separated projections, and chambers located in the ends of said head, of lever-arms pivoted between the projections of the head, and recessed back of their pivots to receive springs; said springs; an incline on the tip of each lever-arm; a tool-holder movable with relation to the head; and inclined projections carried by said tool-holder.

8. The combination, with a head having a tubular shank, and provided with separated projections, of lever-arms pivoted between the projections and having inclined free ends; stops for limiting the movement of said lever-arms; springs bearing against the lever-arms back of their pivots; a tool-holder having a stem fitted in the tubular shank of the head; and plugs carried by said tool-holder, and having inclined upper ends for engaging and swinging said lever-arms.

9. The combination, with a head having separated projections, of lever-arms pivoted between said projections, and each having an inclined forward end; yielding devices for engaging said lever-arms and head; stops for limiting the swinging movement of the lever-arms; a tool-holder movable with relation to the head; and plugs carried by said tool holder, and having inclines at their ends adapted to engage the inclined ends of the lever-arms.

In testimony whereof I affix my signature 85 in presence of two witnesses, at Hartford, Ct. this 24th day of March, 1906.

CLARENCE LEON GOODRICH.
